US0D1097548S

(12) **United States Design Patent** (10) **Patent No.:** **US D1,097,548 S**
(45) **Date of Patent:** **** Oct. 14, 2025**

(54) **CAMERA BAG**

(71) Applicant: **PGYTECH CO., LTD.**, Jiangsu (CN)

(72) Inventor: **Ying Zhang**, Jiangsu (CN)

(73) Assignee: **PGYTECH CO., LTD.**, Kunshan (CN)

(**) Term: **15 Years**

(21) Appl. No.: **29/854,659**

(22) Filed: **Sep. 27, 2022**

Related U.S. Application Data

(63) Continuation-in-part of application No. 29/758,176, filed on Nov. 12, 2020, now abandoned.

(57) **CLAIM**

The ornamental design for a camera bag as shown and described.

DESCRIPTION

FIG. 1 is a front, right perspective view of the camera bag showing the new design;

FIG. 2 is a bottom, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown on the drawings depict portions of the camera bag that form no part of the claimed design.

1 Claim, 8 Drawing Sheets
